UNITED STATES PATENT OFFICE.

ROBERT W. SCOTT, OF BOSTON, MASSACHUSETTS.

ART OF KNITTING RIBBED FABRICS.

1,094,482.

Specification of Letters Patent. Patented Apr. 28, 1914.

Original application filed May 7, 1913; Serial No. 766,092. Divided and this application filed September 29, 1913. Serial No. 792,515.

To all whom it may concern:

Be it known that I, ROBERT W. SCOTT, a citizen of the United States, and a resident of Boston, in the county of Suffolk and State of Massachusetts, have invented a new and useful Art of Knitting Ribbed Fabrics, of which the following is a specification.

An object of my invention is to improve the mode of forming rib webs, for the purpose of insuring the formation of the fabric under conditions imposing a greatly decreased strain on the yarn formed into knit loops, my invention having special value for use in the production of knit webs of fine or coarse gage in which light and delicate yarns are employed.

In the accompanying drawings, Figure 1 is a vertical radial section through the cylinder and dial of a rib knitting machine of a usual type, given as one instance only of a device upon which my method may be practised; Fig. 2 is an underplan of the dial cam cap of such a machine equipped with cams in aid of the performance of operations corresponding to my method; Fig. 3 is a development of the cam cylinder showing the knitting cams for the cylinder needles of such a machine; Fig. 4 is an enlarged section corresponding to Fig. 1 showing the relation of the needles and the yarn during the knitting of a stitch by the dial at one of the knitting points; Fig. 5 is a plan of a portion of the dial needles showing their relation to each other and illustrating the co-action of the needles and yarn; Fig. 6 is a perspective view in the nature of a diagram showing the forming edge of a fabric under construction according to my method.

The knitting or rib webs, essentially requiring the systematic drawing of loops of the course at the edge of the fabric through previous loops in alternate wales, or groups of wales, respectively drawn to opposite faces of the fabric, is usually carried out upon instruments or machines comprising two series of hooked instruments, which conveniently may be latch needles, co-operating with each other to engage the new yarn and draw it through the old loops. Depending upon the choice of instruments or machines, such needles may be fixed in a bar or carrier, or independently movable in succession with respect to the yarn and their carrier, in either case to perform the stated

operation upon the yarn by the relative movement of the instruments and the yarn engaged by them.

In cases where rib fabric is formed by the primary action of one set of needles, and the secondary action of the other set, difficulty is experienced in knocking the old loops carried by the secondary needles over the new loops of yarn which have just been introduced into the hooks of said needles. In all independent needle rib knitting machines with which I am familiar, for instance, the needles are actuated in a successive order with respect to their carriers, one set (that of either carrier, which may be termed primary needles) first drawing their stitches, the intervening yarn being laid over the needles of the other carrier, termed secondary needles, and the latter being then retracted to a point at which the hook of the needle is well within the verge or edge of its carrier before the knocking over of the old loop, which knocking over is accomplished by the combined action of the take-up strain upon the fabric, and the reaction of the verge or edge of the carrier, or instruments at said verge, upon the said loop, tending to prevent it from following the moving needle. But the moving secondary needle engages its new yarn in the middle of a run thereof extending between two adjacent primary loops, in which it is locked and by the distance between which the extent of said yarn is measured. The distance to which said run of yarn may be moved away from the line determined by the surface on which the primary needles operate is thus limited, and in order to move the secondary needle sufficiently far to cause the knocking over of its previous loop a dangerous strain is always more or less present in ribbed webs produced upon instruments so operated. In fine gage machines, in which the distance between two adjacent primary needles is often less than one-sixteenth of an inch, this damage often amounts to a serious loss of tensile strength, and in webs of any gage, its influence upon the selection of yarns capable of being knit is well marked.

In the operation of a prior art machine, for instance such a machine as an independent needle cylinder and dial machine of the type shown in the present drawings, the

needles of both the cylinder 2 and the dial 3 will be actuated to advance them with respect to the verge or edge of their said respective carriers to clear their loops behind their latches, to then engage the new yarn in their hooks (which said operations may be simultaneous), and then the needles of one of the carriers only will be withdrawn into that carrier to draw the old loop through the new loop, a similar operation upon the other carrier following within a short interval. The needles of the first carrier to knit are hereinafter referred to as primary needles and of the second carrier to knit as secondary needles.

Referring now to Fig. 5, the cylinder needles *x* having taken the yarn *Y*, for instance, will all be actuated at *w* to knit one face of the fabric. The needles *x* of the primary carrier having knit, the yarns extending between the knit loops of adjacent needles or groups of needles of said primary carrier will be engaged by the hooks of the advanced needles of said secondary carrier, and it will then become necessary for the needles of the secondary carrier to so perform their operations as to draw the yarn so engaged into loops of proper length for the secondary face of the fabric by a penetrating movement through the old loops engaged upon their shanks. The minimum movement possible for this purpose of pulling the new loop through the old loop (which may be stated with the same meaning as knocking the old loop over the head of the needle on to the new loop) must be made with respect to the fixed line of primary needles, and necessarily is of a dimension sufficient to place the yarn runs now held in the hook of a secondary (dial) needle and engaged at its ends with loops held on the cylinder needles under great strain. The farther the secondary needle is compelled to move before its loop is knocked over, the greater becomes the strain. The mechanical conditions of any type of machine, requiring an open throat for the forming fabric, for instance, between the cylinder 2 and the dial 3, will prevent the moving of the knocking-over verge or edge *v* of the secondary carrier any farther toward the surface occupied by the primary needles.

I have described one way of overcoming the above difficulties in my Patent No. 1,070,191, dated August 12, 1913, which discloses the device of separate instruments for the needles of the secondary carrier, to engage the old loops of that face of the fabric by said instruments, and to positively move the said loops with respect to their needles, to secure knocking over with respect to runs of yarn, the strain on which has been relieved by the release of the primary needles from their stitch-drawing position.

My present method constitutes another way of accomplishing the same ends.

I have devised a new order of performing the operations resulting in the decrease of the strain placed upon the yarn by the operation of the said old instruments, which new order will permit the use of the described old instruments. This method when carried out upon the said old instruments may comprise the steps of feeding the yarn to the primary needles, knitting one face of the fabric with the primary needles, releasing the yarn engaged by the primary needles (except so much thereof as is necessary to pass around the thin metal of the hook of the needle); drawing the yarn intervening between some of said primary needles only through the old loops hanging upon the secondary needles (to knit in some wales only of the other or secondary face of the fabric); relaxing the tension upon the secondary loops so drawn, and thereafter completing the secondary knitting by drawing the remaining runs of yarn intervening between the primary needles through the old loops of the remaining wales of the other or secondary face. I may so order the movements of the instruments as to cause these operations to be successively performed with respect to yarns released and free for this purpose, each secondary needle being given yarn from an adjacent needle not yet retracted and from the previously knit loop or loops near it, sufficient to enable it to make the long movement necessary for knocking over an old loop, and a long loop formed by said needle being in turn released, to be shortened by the long movement of an adjoining needle. It will be understood, however, that the same order of steps may well be performed by moving the yarn loops with respect to relatively fixed needles, the yarn loops being carried in due order to those parts of the needles or instruments upon which they are formed, corresponding with the like parts of the instruments penetrating the loops at the same relative time during the operation of such a machine as I have elected to show and describe herein solely for the purpose of illustrating my method. For instance, the rows of adjacent instruments or needles may be so mounted as to have relative movement with respect to each other, while the individual instruments may either be movable independently, or fixed with respect to each other. In the latter case instruments may be provided relatively movable with respect to said fixed needles, for manipulation or movement of the yarn upon said needles for rib knitting, such as are usually employed in a straight bar or Cotton-type rib knitting machine. I have, however, for convenience described my method in connection with the operation of the cylinder and dial machine above re-

ferred to, which forms the subject of my application Serial No. 766,092, filed May 7, 1913, of which this application is a division.

Referring now to Figs. 1 and 4, in order to practise my invention upon such a cylinder and dial knitting machine, I may divide the secondary needles, shown as the dial needles, into two intercalated sets, which may comprise alternate needles or groups of needles y and y' having their butts at different distances from their hooks to enable independent actuation thereof. As shown the long needles y for the dial may have their operating butts sufficiently inward of those of the short needles y' to enable their respective actuation by cam grooves 4 and 6 of the dial cam cap 5. Said grooves will successively present, in the direction in which the needle butts travel with respect to the cam cap, advancing points 7, on the same radial line, to simultaneously open the latches of the dial needles with respect to the usual yarn feed and latch guard (not shown) which thereafter prevents said latches from closing until the needles are retracted for knitting. Said cam grooves will at a farther point present maximum advancing points 8; for instance upon the radial plane C, Figs. 2 and 3. Coöoperating with the dial cam 8, the cylinder will present an advancing cam 9. Yarn may be fed at the plane C. The cylinder needles are immediately actuated to knit with respect to the advanced dial needles, by the cylinder stitch cam 10, which may as usual be formed as a triangular body, vertically adjustable as by the usual screw and slot adjustment shown at 11 to vary the length of the primary loop drawn by said cam 10 with respect to the dial needles y and y' , which now rest with their latches open and their heads beyond the line of cylinder needles, at the circumferential parts of the cam grooves 4 and 6, shown at 12, 12 Fig. 2. The cylinder needles x having knit, they are immediately advanced by the cam 13 to the position shown in Fig. 4 to pay back or release the yarn drawn by their stitch forming movement. The upper extent of the movement, which is not alone dependent upon the cam 13 for positively giving it, but may in part be caused by the strain put upon the yarn by movement of the dial needles, although I prefer to positively give it by the cam 13, is limited by the guard cam 14, which may be vertically adjustable by means similar to the adjusting screw 11. Immediately upon the attainment of the position shown in Fig. 4 by the needles x , I now actuate one set of the dial needles, shown as the needles y , to perform their knitting movement, and for this purpose provide an adjustable stitch cam 15, having its maximum withdrawal point on the plane G of Figs. 2, 3 and 5. Coöoperating with the stitch cam, the cam groove 6

provides at the point 16 a circumferential portion taking the needles y' to a position in which their hooks are substantially in the line occupied by the hooks of the primary needles at this time, which is the position shown for the needle y' in Fig. 4 and at b in Fig. 5. The cylinder needles x and the dial needles y' have thus been brought into a position at which the minimum possible extent of yarn will pass through the old loops and through the respective hooks, during the time of the stitch forming movement of the needle y , to which enough yarn has been released by the advanced positions of the needle y' and the needle x when in the position of Fig. 4 to enable the free recession of said needle y to draw the new dial loop through the old loop. Immediately following the cam 15 in the groove 4, I may provide an advancing incline 17 coöperating with the needles y to advance them to the position shown at c , e , in Fig. 5, that is to say, to a position at which their hooks are substantially in line with or in advance of the verge of their carrier, to release the strain upon the new yarn loop. During, or preferably following, this movement the needles y' may be retracted to knock over their loops, for instance by the cam 18, which may be a pivoted adjustable stitch cam of the form shown in Fig. 2. Cam 18 is followed by a cam slope 19 to release the needles y' into line with the needles y now in the position e of Fig. 5.

Referring now to Figs. 5 and 6, these movements of the instruments illustrated have carried out the following operations: 1. A loop of a new course has been added to each wale of the face or cylinder side A (Fig. 6) of the fabric. 2. The stress or tension upon the yarn caused by this operation has been relieved, during the formation at some only, or recurrent, wales of loops of the same course on the dial or back face B of the fabric. 3. The loops last formed at the growing edge of the fabric have been released to permit the yarn intervening between said loops and the adjacent loops of face A to be formed into loops of intervening wales of the back face B of the fabric. These matters may be stated in terms of the operation upon the illustrative machine shown as follows: First, the cylinder needles have knit with respect to dial needles thrown out to engage the sinker wales between said cylinder needles, and said cylinder needles have then been released to a position at which they place the minimum possible tension upon the loops of the new yarn just knit; second, certain of the dial needles shown as alternate needles have then performed their knitting movements during such time as the intervening needles of the dial have also been placed in a position to put no strain upon the new yarn held in

their hooks, that is to say at the position *b* of Fig. 5, and thus to permit their yarn to be used by the needles *y* following them to draw elongated stitches sufficient to knock over their old loops; third, the needles of the dial which had been in a position of rest to release their loops for this purpose then have operated during or after the release of the new loop by the following needles of the 10 other dial series, also to permit the use of a part of the yarn employed in the knocking-over operation of the first series of secondary needles to knit. Thus a dial stitch on a needle *y* is robbed or gives up some of its 15 yarn to aid a needle *y'* to knit. The last needle of the secondary carrier to knit, as described a short needle *y'*, will now hold loops *n'* slightly enlarged at the expense of the loops *n* of their flanking needles *y*, and 20 larger than the loops *o* of the neighboring cylinder needles *w*; but, as will readily be apparent, the mean or average size of the dial loops and the cylinder loops will be substantially only one-half that necessary for 25 the knocking-over operation under normal conditions, if the adjustments are such as to cause a recession of the secondary needles into their carrier only sufficient to permit knocking-over at the times of their maximum withdrawal, and by the described operations of 30 the secondary needles in two sets, one of which knocks over previously to the other, I have thus provided sufficient new yarn to be moved through the old loop, without having 35 provided sufficient new yarn to permit these operations to be performed simultaneously, or by successive drawing movements of adjacent secondary needles. I may, if necessary, now adjust the short loops which have been 40 knit by subjecting them to alternate or successive stresses from each face of the fabric, as by providing an adjustable retracting cam for the cylinder, shown at 20, and adjustable retracting cams 21 and 22 for the needles *y* 45 and *y'* of the dial. While I have shown the cam 20 in a position to precede in effect the operative position of cams 21 and 22, it is obvious that these positions may be reversed. The effect of these cams is as indicated at 50 Figs. 5 and 6 at *p* to adjust or distribute the yarn now completely interknit between the loops *n*, *n'* of the back or dial face of the fabric and the loops *o* of the front or cylinder face thereof.

55 When carrying out my method upon a multiple or double course machine such as that usually employed for wide fabrics, I prefer to reverse the order at which the needles *y* and *y'* knock over their loops at the 60 second feed or course; for instance, instead

of the cam 15 having its stitch forming point in the groove 4 in advance of the stitch forming point of the cam 18 in the groove 6, I may provide at the next yarn feed in the groove 4 a knitting cam 150, to knock over 70 the needle *y* at a later time than the needles *y'*, which will be operated by a cam 180 of the form and at the position shown. The cylinder cam for the second feed or unit may, however, remain unaltered, comprising 75 the cams 9, 10, 13, 14 and 20.

My invention is readily applicable, it will be understood without specific illustration, as well to rib knitting characterized by the formation on one or both faces of persistently tucked loops, for instance in connection with the making of Cardigan or half-Cardigan fabrics, as to the regular rib knitting shown and described as one illustrative instance. Machines for the said purposes may, as usual, be provided at alternate feeds or groups of feeds in both, or in one of the carriers only, respectively for said Cardigan and half-Cardigan knitting, with stitch cams having any usual structure for tucking 85 at that feed. Usual constructions for this purpose may comprise advancing cams insufficiently high to clear the needles, or stitch-cams of insufficient loop-drawing extent to knock over the loops. When such 90 cams are in use, the described knocking-over operation will be delayed to another or later course, with an accumulation of loops at the needles concerned, but when said knocking-over does take place, it will be with respect 95 to neighboring needles advanced to a loop-relieving position in the manner I have fully described.

It will be apparent that, while I have described my method in connection with a circular rib knitting machine, the same movements of the needles with respect to their carriers and each other may well take place in rib knitting machines of the straight or flat bed type, and that the knitting instruments might be spring needles, capable of drawing the yarn with respect to a knocking-over verge, edge or row of auxiliary instruments as well as latch needles, and that the practice of my method in these cases 105 would produce the same improved results.

What I claim is:—

1. The art of knitting ribbed webs comprising first knitting a course of loops on one face of the fabric, then knitting loops 110 of the same course in separated wales of the other face of the fabric, and then knitting loops in the intervening wales of said other face.

2. The art of knitting ribbed fabrics comprising the formation of successive courses by first forming from a run of yarn sufficient to form all the loops of both faces of the fabric knit loops of said yarn penetrating the old stitches of one face of the fabric, 125 130

subsequently drawing loops of said yarn through some only of the old stitches of the other face of the fabric, and then drawing loops of said yarn through the remaining old stitches of said other face of the fabric.

5. The art of knitt'g ribbed fabrics comprising the following steps; first knitting a course of loops in all the wales of one face; then drawing the yarn intervening between some of the said wales through some only of the previous loops of the other face, and then drawing the remaining parts of the yarn intervening between face wales through the remaining previous loops of said other face.

15. 4. The art of forming ribbed fabric comprising knitting a course of the primary face of the fabric and thereafter completing said course in the secondary face of the fabric by knitting a plurality of intercalated series of loops in succession, the loops of the first of said series being completed and relaxed prior to the knitting of the remainder of said series of loops.

5. The art of knitting ribbed webs on two sets of needles, comprising feeding a yarn to the needles, then actuating one set of needles to knit loops of said yarn through the loops of a previous course on one face of the web; then actuating a series of needles distributed among the needles of the other set to knit said yarn through other loops of said previous course, and then actuating the remaining instruments of said other set to knit said yarn through all the remaining loops of said previous course.

6. The method of knitting ribbed fabric upon at least two sets of instruments comprising feeding the yarn to the instruments of said sets, knitting upon one face of the fabric by causing loops of said yarn to penetrate loops of previously formed fabric held at instruments of one of said sets only, then causing the yarn intervening between said knit loops to be knit upon the other face of the fabric at the location of some of the instruments only of another set of said instruments, and thereafter knitting the yarn intervening between the previously knit loops at the location of the remaining instruments.

50. 7. The method of knitting ribbed fabric which comprises the formation of a new course upon a previously knit section of such fabric by first forming a new yarn into a

successive series of primary loops penetrating the terminal loops of the previous fabric 55 in all of the wales of one face of the web, and in successively thereafter forming of the alternate runs of yarn extending between said loops secondary loops; in drawing said secondary loops through the terminal loops 60 of the corresponding wales of the other or back face of the web, and in thereafter drawing the remaining runs of yarn extending between said primary loops into loops penetrating the remaining wales of the back face 65 of the web.

8. The method of knitting ribbed fabric upon two intercalated sets of hooked instruments, comprising supplying yarn to the hooks of both sets of said instruments, and 70 then drawing the yarn at one set of instruments into loops penetrating previous loops of one face of the fabric; in thereafter relaxing the new or last formed loops by relative movement between the fabric and the instruments upon which said loops were formed 75 and are held; in thereafter operating upon the yarn at the location of alternate instruments of the other set, first to cause the yarn runs intervening between loops of the first 80 knit face at certain only of said instruments distributed among said other set to be drawn in succession through the old loops of the other or back face of the fabric, and thereafter to cause said loops to be relaxed in 85 succession; and in thereafter operating upon the yarn at the location of the remaining instruments of said other set to draw loops toward said back face of the fabric.

9. The art of knitting ribbed webs comprising first knitting a course of new loops on one face of the fabric, then knitting loops of the same course in separated wales only of the other face of the fabric, then knitting loops in the intervening wales of said other 95 face, and then subjecting the loops of both faces to successive stresses to adjust the length of the loops.

In testimony whereof, I have signed my name to this specification in the presence of 100 two subscribing witnesses.

ROBERT W. SCOTT.
